FIG. 1 is a top perspective view of a wiper according to my new design;

FIG. 2 is a bottom perspective view thereof;

FIG. 3 is a rear plan view thereof;

FIG. 4 is a front plan view thereof;

FIG. 5 is a top plan view thereof;

FIG. 6 is a bottom plan view thereof;

FIG. 7 is a left-side plan view thereof;

FIG. 8 is a right-side plan view thereof;

FIG. 9 is a cross-sectional view thereof taken along view IX-IX of FIG. 5;

FIG. 10 is a cross-sectional view thereof taken along view X-X of FIG. 5;

FIG. 11 is a cross-sectional view thereof taken along view XI-XI of FIG. 5;

FIG. 12 is a cross-sectional view thereof taken along view XII-XII of FIG. 5;

FIG. 13 is a cross-sectional view thereof taken along view XIII-XIII of FIG. 5; and,

FIG. 14 is a cross-sectional view thereof taken along view XIV-XIV of FIG. 5.
